UNITED STATES PATENT OFFICE.

STEVE PLESEC, OF SAN FRANCISCO, CALIFORNIA.

COMBINATION CHAIR.

Application filed September 15, 1921. Serial No. 500,758.

To all whom it may concern:

Be it known that I, STEVE PLESEC, a citizen of Jugoslavia, residing at San Francisco, in the county of San Francisco and 5 State of California, have invented certain new and useful Improvements in Combination Chairs, of which the following is a specification.

The primary object of the invention is 10 the provision of a combination chair and stepladder, serviceable as a comfortable chair and readily convertible into a three-step ladder whereby the device may be used as a strong and safe stepladder.

15 A further object of the invention is the provision of a chair having step portions provided in the seat and back thereof, adapted for ready shifting for use as a stepladder, the arrangement being such as to 20 lock the steps in their shifted positions.

A still further object of the invention is to provide a stepladder chair that is simple and strong in construction, easy and inexpensive to manufacture and at the same 25 time, is fully serviceable as a chair when desired and readily changed to a stepladder whenever the occasion requires.

With these general objects in view, the 30 invention consists in the novel combination and arrangement of parts hereinafter more fully described in connection with the accompanying drawing and in which like reference characters designate corresponding parts throughout the several views.

35 In the drawing,

Figure 1 is a front elevation of the invention,

Figure 2 is a side elevation thereof illustrating by dotted lines the position of the 40 parts when the device is employed as a stepladder,

Figure 3 is a transverse sectional view upon line 3—3 of Figure 2, and

Figure 4 is a perspective view of a portion of the transverse brace.

Referring more in detail to the drawing, my invention broadly consists of a standard chair of substantially the usual form with front legs 10 and opposite side rails 50 11 for connecting the upper ends of the legs 10 with the rear legs 12 as at 13, the rear legs being extended upwardly forming sides 14 for the back of the chair. The chair bottom consists of two parts 15 and 55 16, the part 15 being permanently secured between the rails 11 forming the rear por-

tion of the seat adjacent said sides 14. The bottom portion 16 is hinged as at 17 to the rails 11 and seats within opposite notches 18 of the rails 11 when in its horizontal position as illustrated in Figure 2 with the upper surfaces of the members 15 and 16 in horizontal alinement presenting substantially an unbroken chair bottom of wood or other similar material. A rolled-over forward edge 19 is preferably provided upon the front sections 16 of said bottom which is positioned adjacent the sides 14 when the section 16 is swung upon its hinges 17 for alining flatly upon the bottom portion 15 60 as illustrated by dotted lines in Figure 2.

Lower side rails 20 between the legs 10 and 12 beneath the upper rails 11 have a lower step 21 mounted thereon between the front legs 10 and directly beneath the opening formed by the bottom portion 16 when in its shifted turned-back position. The forward ends of the lower rails 20 preferably project forwardly of the front legs 10 with the forward edge of the step 21 corresponding to the end faces of said rails 20. A suitable bar or connecting round 22 is positioned between the upper ends of the sides 14 in the usual manner. A connecting brace 23 is secured between the sides 14 beneath 75 the rod 22 by upturned angular ends 24 fastened by means of screws or other similar devices 25 to the rear edge of the sides 14. An upper step 24 is pivoted by means of trunnions 25 between the opposite sides 14 80 in a position for engaging the horizontal flat connecting brace 23 when said upper step 24 is swung to its horizontal position in the stepladder arrangement of the device as illustrated by dotted lines in Figure 2 of the 95 drawing.

Rods 26 are pivotally connected between the forward bottom portion 16 and the upper step 24, such connection insuring the substantially vertical position of the upper 100 step 24 between the sides 14 and constituting a part of the chair back when the bottom portion 16 is forwardly positioned as a part of the seat as illustrated in Figures 1 and 2. The lower pivotal connections 27 105 of the rods 26 are at the outer sides of the front portion 16 adjacent the hinges 17 while the upper pivotal connections 28 of the rods 26 are with suitable lugs 29 provided upon the upper and outer face of the 110 upper step 24, with the rods 26 outwardly of the sides 14.

Referring more in detail to the drawings, the formation of the chair with its movable parts will be fully understood from the foregoing description as well as the manner of 5 moving the bottom portion 16 upon its hinges 17 to automatically shift the combined back panel and upper step 24 to its flat horizontal position for use as a step as illustrated by dotted lines in Figure 2. The 10 pivot points 27 are so positioned upon the chair bottom member 16 with respect to the hinge 17 as to be brought off-center when the portion 16 is turned back with the upper step 24 horizontal which results in locking 15 the upper step 24 in position flatly engaging the bottom of the brace 23 so that the weight of a person upon the upper step 24 will be partly borne by the brace 23 and the step 24 prevented from pivoting upon 20 the trunnions 25 by reason of said locking position of the rods 26. The opening in the chair bottom caused by rearwardly shifting the portion 16 permits a person to readily mount upon the lower step 21, then upon 25 the rearwardly turned bottom portion 16 as a second or intermediate step and then upon the upper horizontal step 24. By returning the panel portion 16 to its normal place in said formation, the rods 26 automatically 30 bring the upper step 24 into its position as a back panel engaging the forward edge 30 of the brace 23 as shown in Figure 1.

While the form of the invention herein set forth is believed preferable, it will nevertheless 35 be understood that minor changes may be made therein without departing from the spirit and scope of the invention.

What is claimed as new is:

1. A stepladder chair comprising forward and rear legs, upper and lower connecting braces therefor, a lower step secured to the lower braces between said front legs and projecting forwardly thereof, a two-part seat for the chair carried by said upper braces, hinge connections between the forward part of said seat and said upper rails whereby an interrupted portion is adapted to be formed in the seat for permitting use of said lower step, the hinged seat portion being adapted for rearward swinging movement for use as a second step, opposite sides for the chair back at the upper ends of the rear legs, a combined upper step and back panel pivoted between said sides above the seat and link connections between said panel and the hinged seat section to cause both of the same to assume their chair or step-ladder formation at will, the point of connection between the link and hinged seat 60 and panel sections, being respectively, forwardly of the hinged seat section and below the pivot of the panel section for holding the seat and panel sections in locked position when swung rearwardly, with said sections being simultaneously shifted by the 65 link connection.
2. A stepladder chair comprising forward and rear legs, upper and lower connecting braces therefor, a lower step secured to the lower braces between said front legs and projecting forwardly thereof, a two-part seat for the chair carried by said upper braces, hinge connections between the forward part of said seat and said upper rails whereby an interrupted portion is adapted to be formed in the seat for permitting use of said lower step, the hinged seat portion being adapted for rearward swinging movement for use as a second step, opposite sides for the chair back at the upper ends of the rear legs, a combined upper step and back panel pivoted between said sides above the seat, a brace between said sides adapted for seating engagement with said panel when in either its step or back forming position and link connections between said upper step and hinged seat portion adapted for the simultaneous shifting thereof at will, the point of connection between the link and hinged seat and panel sections, being respectively, forwardly of the hinged seat section and below the pivot of the panel section for holding the seat and panel sections in locked position when swung rearwardly, with said sections being simultaneously shifted by the 70 link connection.
3. A stepladder chair comprising forward and rear legs, upper and lower connecting braces therefor, a lower step secured to the lower braces between said front legs and projecting forwardly thereof, a two-part seat for the chair carried by said upper braces, hinge connections between the forward part of said seat and said upper rails whereby an interrupted portion is adapted to be formed in the seat for permitting use of said lower step, the hinged seat portion being adapted for rearward swinging movement for use as a second step, opposite sides for the chair back at the upper ends of the rear legs, a combined upper step and back panel pivoted between said sides above the seat, opposite links pivotally connected outwardly of said sides between the upper step and the hinged seat portion whereby the upper step is locked horizontally when the seat portion is in its rearwardly swung position horizontally in ladder formation, the point of connection between the link and hinged seat and panel sections, being respectively, forwardly of the hinged seat section and below the pivot of the panel section for holding the seat and panel sections in locked position when swung rearwardly, with said sections being simultaneously shifted by the 75 link connection.

In testimony whereof I affix my signature.
STEVE PLESEC.
